MACHINE FOR SHARPENING KNIVES FOR
PLUSH AND VELVET CUTTING

Willy Trüjen, Erkelenz-Rhineland, Germany

Application January 29, 1937, Serial No. 123,029
In Germany May 18, 1936

1 Claim. (Cl. 51—247)

The present invention relates to a machine for the sharpening of knives for plush and velvet cutting.

I have made applications as follows: in Germany, on May 18, 1936; in Belgium, on October 22, 1936; in France, on October 26, 1936; in Italy, on November 3, 1936; in Great Britain, on December 12, 1936.

The devices known up to the present for sharpening this type of knife have the disadvantage that the sharpening is not perfect, from which it results that the threads, instead of being cut, are often torn.

The object of the present invention is to avoid this inconvenience. For this purpose, the grinding wheel revolves in an opposite direction in relation to the knife which comes into contact with it.

In the attached drawing, there is represented, by way of example, a form of realisation of the present invention.

Fig. 1 is a vertical longitudinal section of the sharpening machine.

Fig. 2 is a plan view showing the operative relation of the grinder to the loom knife.

Fig. 3 is a section following the line A—B of Fig. 1.

Figs. 4 and 5 show a plan and a side view of the control lever of the grinding wheel.

On the loom batten, working with a backward and forward motion, there is screwed by means of a wood screw, a square, on which is fixed a flat iron *a* adjustable longitudinally by means of a slot *a'*. On this flat iron *a* there is fitted a pressure roller *b*. With every stroke of the batten, this pressure roller *b* pushes the lever *c* towards the front, the lever being brought back to its original position by a spring *d*. By means of gear wheels *j*, *u* and *e*, the movement of the lever *c* causes the last mentioned gear wheel *e*, which is locked on the axle *p* by means of a ball and socket joint, to revolve.

The grinding wheel *f* revolving with the journal in the opposite direction to that of an ordinary plush-cutting knife with a cutting edge in the form of a semi-circle, is mounted on the axle *p*. The journal *p* penetrates upwards in a notch of a cover or lid *h*, and is maintained in its perpendicular position by a spring with two arms *g*, that is to say, in the form of a hair-pin. The cover or lid *h* may slope, in revolving for example round a pivot *s*, and is then kept in the desired position by means of a locking nut *s'*, this being for the purpose of giving to the grinding wheel in its rest position, another obliquity, or when it

is in movement, an obliquity corresponding to the position of the knife to be sharpened. Near the top of the cover *h* is a hole in which is placed a square piece *i* in which are two holes through which the arms of the spring *g* pass. Through the sliding movement of the square piece *i*, the part of the spring *g* acting on the journal *p* extends or shortens, thus giving either a slack or strong tension. In order to prevent any overrunning of the grinding wheel, the gear wheel *j*, on which is fixed a ratchet *k* acting on the lever *c* is braked by means of a spring *l*, the pressure of which may be regulated by a screw *t*. The apparatus is fixed to the cutting board of the loom by a square plate *m*, slotted on its two faces, in order to allow of its adjustment either in a forward, backward, upward or downward direction. This ensures the possibility of the apparatus being applied to any system of loom.

The control of the sharpening machine is placed in a cast metal casing *n* closed by a cover or lid *o* by means of two screws. The apparatus begins to function when the knife approaches the outside edge of the loom. Owing to the fact that the rotation is in the opposite direction of the grinding wheel in relation to that of the knife, almost a double sharpening force is obtained. It is possible to use the thinnest grinding wheels of 50%; previously it was necessary to use coarse grinding whels, which caused notches on the edge of the knife and consequently bad cutting of the material, and grooves which were formerly inevitable in curved grinding wheels, are avoided in a definite manner, by these rotating grinding wheels.

The stone may be used on both sides, and lasts at least twenty times longer than those previously in use, without showing any unevennesses. The setting of the two edges of the grinding wheel which was previously carried out with a file or on an emery wheel, is now effected on an ordinary small wheel by using diamond dust, that is on a lapidary wheel, and takes only a few minutes for the operation.

The sharpening machine is adjustable in order to give the grinding wheel either a small or large rotation, according to the desired sharpening of the knife and according to the material to be woven, by means of a screw *q* which regulates the stroke of the lever *c*. A change of grinding wheel is therefore no longer necessary except for the types of weaving requiring a special cutting, and according to the case, the apparatus is adjusted for small or large rotation.

I claim:

A knife sharpening machine for plush and velvet cutting, comprising a circular grinding wheel with an edge of conical section supported by a loom and mounted on an axle, one end of which being supported by a ball and socket joint, the other end being maintained by elastic means

for an intermittent engagement of the grinding wheel with a knife, and means operated by a loom batten for rotating intermittently said grinding wheel in timed relationship with the knife and in the direction opposite to the latter. 5

WILLY TRÜJEN.
